(57) **CLAIM**

The ornamental design for a cutting insert, as shown and described.

DESCRIPTION

FIG. 1 is a front, perspective view of a cutting insert showing our new design;

FIG. 2 is a rear, perspective view of the cutting insert of FIG. 1;

FIG. 3 is a top view of the cutting insert of FIG. 1; FIG. 4 is a bottom view of the cutting insert of FIG. 1; FIG. 5 is a left side view of the cutting insert of FIG. 1; FIG. 6 is a right side view of the cutting insert of FIG. 1; FIG. 7 is a top view of the cutting insert of FIG. 1; and, FIG. 8 is a rear view of the cutting insert of FIG. 1.

The broken-line disclosure in the views is for illustrative purposes only and forms no part of the claimed design.
